CONTACT LENS CASE

David L. Nathan, Maplewood, N.J., assignor to
Opticase, Inc., Rockaway, N.J.

Filed Dec. 1, 1971, Ser. No. 203,942

Term of patent 14 years

Int. Cl. D16—06

U.S. Cl. D57—1 B

FIG. 1 is a top plan view of a contact lens case embodying my new design, the case being shown in fully open position;

FIG. 2 is a left end elevational view thereof;

FIG. 3 is a right end elevational view thereof;

FIG. 4 is a side elevational view thereof;

FIG. 5 is a side elevational view showing the case in partially closed position; and

FIG. 6 is a side elevational view showing the case in fully closed position.

I claim:

The ornamental design for contact lens case, as shown and described.
